UNITED STATES PATENT OFFICE.

JUSTUS C. LAWLER, OF TRINIDAD, COLORADO.

INTERNAL-COMBUSTION ENGINE.

1,111,074.

Specification of Letters Patent.

Patented Sept. 22, 1914.

Application filed May 23, 1911. Serial No. 628,932.

To all whom it may concern:

Be it known that I, JUSTUS C. LAWLER, a citizen of the United States, and resident of Trinidad, in the county of Las Animas, State of Colorado, have invented certain new and useful Improvements in Internal-Combustion Engines, of which the following is a specification.

The present invention relates to improvements in internal combustion engines and has for its object to provide a light and compact engine structure by which a maximum amount of power may be economically obtained.

In particular the invention has for its object to provide means by which the amount of each explosive charge is greater than that which would be introduced into the combustion chamber by the displacement of the piston at atmospheric pressure, and further to cause a greater compression of such explosive charge than is commonly effected.

In the accompanying drawings: Figure 1 is a view in partial elevation and partial section of an internal combustion engine constructed in accordance with the present invention; Fig. 2 is an elevation from the opposite side of the engine shown in Fig. 1; Fig. 3 is a sectional view illustrating a slightly different form of engine from Figs. 1 and 2; Fig. 4 is a sectional view on an enlarged scale of one of the pistons; Fig. 5 is a transverse sectional view substantially on the line 5—5 of Fig. 4; Fig. 6 is a sectional view through the engine on substantially the line 6—6 of Fig. 3; Figs. 7 to 11, inclusive, are respectively sectional views on the lines 7—7, 8—8, 9—9, 10—10 and 11—11 of Figs. 3 and 6, the pistons being omitted; Fig. 12 is a transverse sectional view through a portion of the crank shaft and its bearing.

While the invention may be applied to or embodied in engines of various types it has for the purposes of the present application been shown as modified in engines of the "two-cycle" class, and in Figs. 1 and 2 there is shown an engine of this type comprising four cylindrical casings A, A', A² and A³. Each of said casings is of such form that there is provided therein a working cylinder or combustion chamber a and a pumping cylinder b, the latter being of greater diameter than the combustion or working cylinder and communicating with the crank case c. The several working cylinders are surrounded by water jackets D

with which communicate supply and discharge pipes d, d'. Each working cylinder is further provided with an inlet port a' and with suitable igniting devices conventionally illustrated at a².

Within each casing of the engine is arranged a piston shown as being of hollow cylindrical form and having a body section E coöperating with and working within the cylinder a and an extension E' of greater diameter than the body which constitutes a piston for the pumping cylinder b. The piston is connected by a suitable link or rod e with a crank f on a shaft F. The latter is mounted in suitable bearings in the crank case of the engine and preferably it is provided with an aid conduit as will be herein-after described for supplying air to the crank case and pumping cylinder b. As shown in Fig. 4, the piston is preferably made of two sections connected by a threaded joint e', and both of the piston heads formed thereon are provided with grooves to receive packing or expansion rings to prevent leakage between the piston and wall of the cylinder in which it works.

According to the present invention the pump cylinder b and crank casing e are employed to receive, and the piston acts to compress therein, the air which is afterward supplied to a carburetor and forms the body of the explosive charge or mixture supplied to each working or combustion cylinder. Further, the several cylinders are so connected that each piston is caused to compress air throughout its entire movement and thereby the pressure of the explosive charge supplied to each working cylinder is in excess of that which would be obtained by the displacement of the piston in such cylinder alone.

In the form of the invention shown in Figs. 1 and 2 the crank case or lower portion of each pumping cylinder is connected by a pipe G with another pumping cylinder and on the opposite side of the piston therein. That is, the crank case or lower end of the pumping cylinder b of the casing A, for example, is connected with the upper portion of the corresponding cylinder b of the casing A', and the casings A² and A³ are similarly connected. It will be understood that according to the present invention the pumping and working cylinders are arranged in pairs and it will be seen that by such arrangement and the connection just de-

scribed each piston will operate throughout its movement to compress air in the cylinder *b* in which it works.

Air is admitted to each cylinder through the hollow crank shaft *F* which is provided at suitable points with a slot or slots *s* adapted to pass across corresponding inlets *s'* formed in the shaft bearing whereby the motion of the pistons will act to draw air into the chambers *b* as the piston in each of said chambers moves upwardly to compress the explosive charge in the working cylinder *a*. The amount of air admitted to each pumping cylinder in the manner described may be controlled and regulated by any suitable valve mechanism, a simple form being illustrated at *H* in Fig. 2. The several pumping cylinders *b* are all adapted to communicate with a common conduit or duct *I* for compressed air, which in turn is connected through a manifold with the inlet ports of each working cylinder, a suitable carbureter being inclosed within such manifold. In the form of the invention illustrated in Figs. 1 and 2 the said manifold comprises two branches *O*, *O'*, which are connected at their ends by a member *O*² which has direct communication with the inlet ports of the several working cylinders. As the carbureter may be of any suitable style it is illustrated conventionally only, as by dotted lines *K*, in Fig. 2, the conduit for supplying gasoline to such carbureter being indicated at *K'*.

The connection between each of the pumping cylinders *b* and the compressed air duct or conduit *I* is controlled by the piston in such cylinder. As shown there are formed in the body of the piston above the head *E'* thereof a series of longitudinally extending grooves *e*² which are of such length that when the piston is reaching the limit of its upward movement they establish communication between the chamber *b*, in which the piston moves, and said conduit or duct *I*, as shown, for example, in Fig. 1. With the parts in this position the charge of air previously compressed in the upper portion of the pumping cylinder *b* of the engine casing will pass into said conduit *I*. Near the lower end each working or combustion cylinder *a* is provided with a series of exhaust apertures or ports *a*³. These ports are shown as extending substantially around the cylinder and providing a relatively large exhaust area, and they are so arranged that the expanding gas is retained in the cylinder until near the end of the downward or outward stroke of the piston.

As hereinbefore described the several cylinders of the engine are arranged in pairs and as shown in Figs. 3 to 12 such a pair of cylinders may be cast integrally thus providing a very compact arrangement. Also instead of employing exteriorly arranged conduits or pipes *G* for conducting air from a

point below the downward limit of movement of the piston in one pumping cylinder to a point above the upward movement of the corresponding piston in the coöperating cylinder, such conduits are formed within the engine casings as represented in Fig. 11. In said figure *L* represents the passage which communicates with the crank case of pumping cylinder *b'*, Fig. 3, and with the upper portion of the adjacent pumping cylinder *b*² through ports *l*. Similarly the crank case below cylinder *b*² is connected through a passage *L'* with ports *l'* opening into the pumping cylinder *b'*.

In the embodiment of the invention now referred to the compressed air duct or conduit *I'* communicates through a duct *M* with the manifold *N* in which is arranged the carbureter and the branches of which communicate with the inlet ports of the cylinders, such ports being controlled by suitable valves *N'*.

As shown in Figs. 3 and 12 the supply of air to the ports in the bearing for the hollow crank shaft *F* may be controlled by a valve *P* mounted at the upper end of a suitable casing surrounding the ports in said bearing.

From the foregoing description and the drawings the operation and advantages of an engine constructed in accordance with the invention will be easily understood.

It will be seen that the pumping piston *E'* of each pair of coöperating pistons will effect a maximum compression of air at the same time that the other corresponding piston of said pair moving in the opposite direction effects a similar compression and that the air thus compressed by both said pistons will be caused to pass into the common compression duct or channel as either of the pistons in the working cylinders approaches the limit of its compression stroke. The air thus compressed is conveyed to a sealed receptacle containing a carbureter or similar device which in turn is connected with the inlet ports of the several working cylinders. Gasoline if combined with the compressed air for forming the explosive mixture must be admitted through the carbureter at a pressure greater than that of the air, and this may be accomplished by means of a suitable pump or by the relative arrangement of the gasoline tank and carbureter.

By the invention it will be seen that the crank case is employed only for compressing air and therefore the lubrication of the bearings of the crank shaft are not affected as they are when the crank case is employed for compressing the explosive mixture as has been the practice commonly followed in two-cycle engines. Further, the invention employs but a single carbureter for a plurality of cylinders thus reducing the number of parts to a minimum. By uti-

lizing the crank shaft as an air inlet valve no supplemental or special valve has to be provided so that the power commonly required to operate such valve is saved.

5 Again it will be seen that all of the valves of the engine are readily accessible and can be renewed or repaired without great inconvenience.

The inlet and exhaust ports of each working cylinder are arranged adjacent opposite ends thereof so that each cylinder may be completely scavenged following an explosion without loss of explosive mixture through the exhaust ports. This arrangement permits of the exhaust ports extending substantially around the cylinder and giving a longer power stroke to the piston without decreasing the area of the exhaust openings.

20 In engines of this type as commonly constructed the amount of mixture supplied to the cylinder during each cycle of movement of the piston is generally less than the capacity of the cylinder and the valve controlling the inlet port normally closes before the exhaust port is closed. By the present invention however any desired quantity of mixture may be supplied to the cylinder by properly proportioning the compressor 25 and as the mixture can enter the cylinder after the exhaust port is closed there is no danger of any loss of such mixture through the exhaust port.

Having thus described my invention, what 35 I claim and desire to secure by Letters Patent is:

1. In an internal combustion engine, the combination of a suitable casing having therein a pair of cylinders, each cylinder 40 provided with an inlet at the head end and an outlet at the crank end, means for igniting a charge in each cylinder, a piston working in each cylinder and having an extension coöperating with the casing to provide an air pump, a mixing device having its mixture outlet connected with the inlets of both cylinders, and a duct connected with the inlet of the mixing device and with the engine casing in such a manner that the 45 mixing device will receive all the air compressed by both pumping pistons throughout the strokes thereof.

2. In an internal combustion engine, the combination of a suitable casing having therein a pair of working cylinders each 55 provided with an inlet at the head end and an outlet at the crank end, means for igniting a charge in each cylinder, a piston with in each cylinder having an extension coöperating with the casing to provide a pump acting throughout the entire reciprocating movement of the piston to compress air, a carbureter having its mixture outlet connected with the inlets of both working 60 cylinders, and means connecting both of

said air pumps with the inlet of the carbureter in such a manner that the carbureter will receive all the air compressed by both pumping pistons throughout the strokes thereof and while said pistons are moving 70 in opposite directions.

3. In an internal combustion engine, the combination of a casing having therein a pair of working cylinders, provided with inlet ports at their head ends, and exhaust 75 ports at the crank ends of the cylinders, means for igniting a charge in each of said cylinders, a pair of pump cylinders, a piston within each working cylinder, a piston in each pumping cylinder connected with a 80 piston in a working cylinder, an inlet for admitting air to each pump cylinder, connections between the pump cylinders within the casing and extending from one side of the piston in each cylinder to the opposite 85 side of the piston in the other, a carbureter having its mixture outlet directly connected with the inlet ports of both working cylinders, and direct connections between the carbureter and both pump cylinders said 90 pistons in the pumping cylinders acting throughout their entire reciprocating movement to compress the air supplied to said carbureter.

4. In an internal combustion engine, the combination of a pair of working cylinders, provided with inlet and exhaust ports at the head and crank ends of the working cylinders respectively, means for igniting a charge in each of said cylinders, a pair 95 of pump cylinders in alignment with and of greater diameter than the working cylinders, a piston within each working cylinder having an extension terminating in an enlarged head within the aligned pump cylinder, an inlet for admitting air to each pump cylinder on the opposite side of the head of the piston therein from the working cylinder, connections between the pump cylinders, extending from one side of the piston 100 head in each cylinder to the opposite side of the piston head in the other, whereby said pistons in the pump cylinder may act throughout their reciprocating movement to compress air, a carbureter having its mixture outlet directly connected with the inlet ports of both working cylinders, and direct 105 connections between the carbureter and both pump cylinders the carbureter receiving all the air compressed by both pumping pistons throughout the stroke thereof and while the pumping pistons are moving 110 in opposite directions.

5. In an internal combustion engine, the combination of a casing having therein two 115 sets of aligned working and pumping cylinders, the former each having inlet and exhaust ports, means for igniting a charge in each working cylinder, a carbureter having its mixture outlet connected with the in- 120

lets to both working cylinders and its air inlet connected with a supply duct, a piston in each working cylinder having an extension constituting a piston in the alined pump cylinder, the body of each piston having formed therein a passage adapted in one position to connect its pump cylinder with the air supply duct of the carbureter, an inlet for air in each pump cylinder, and ducts connecting the pump cylinders and each extending from one side of the piston in one of said cylinders to the opposite side of the piston in the other said cylinder.

6. In an internal combustion engine, the combination of a pair of working cylinders, provided with inlet and exhaust ports, means for igniting a charge in each of said cylinders, a pair of pump cylinders, a piston within each working cylinder, a piston in each pumping cylinder connected with a piston in a working cylinder, an inlet for admitting air to each pump cylinder, connections between the pump cylinders extending from one side of the piston in each cylinder to the opposite side of the piston in the other, a carbureter having its mixture outlet connected with the inlet ports of both working cylinders and having an air supply duct adapted to communicate with said pump cylinders, and means controlled by the pistons for establishing communication between said duct and the pump cylinders.

7. In an internal combustion engine, the combination of a pair of working cylinders, provided with inlet and exhaust ports, means for igniting a charge in each of said cylinders, a pair of pump cylinders in alinement with and of greater diameter than the working cylinders, a piston within each working cylinder having an extension terminating in an enlarged head within the alined pump cylinder, and provided in its exterior surface adjacent said head with a plurality of longitudinally extending grooves or channels, an inlet for admitting air to each pump cylinder, connections between the pump cylinders, extending from one side of the piston head in each cylinder to the opposite side of the piston head in the other, and a carbureter having its mixture outlet connected with the inlet ports of both working cylinders, and its air inlet directly connected with a duct adapted to communicate with both pump cylinders through the aforesaid grooves or channels in the pistons.

8. In an internal combustion engine, the combination of a pair of working cylinders provided with suitable inlet and exhaust ports located at opposite ends thereof, ignition means at the inlet ends of said working cylinders, a pair of pumping cylinders in alinement with the working cylinders, pumping pistons in the pumping cylinders and compressing air throughout the strokes thereof, means including a duct connect-

ing the pump cylinders with the inlets of the working cylinders, a carbureter located in said duct and arranged to mix fuel with all the air supplied to said working cylinders, said pumps compressing the air to such a pressure that the amount of explosive mixture supplied to the working cylinders will be greater than that supplied by the displacement of the working pistons only.

9. In an internal combustion engine, the combination of a plurality of working and air pumping cylinders, pistons in the pumping cylinders capable of compressing air throughout their strokes in both directions, a carbureter or mixing device having its mixture outlet connected with the inlet of each working cylinder, and means whereby substantially all the air compressed in the pumping cylinders is supplied to the inlet of said carbureter.

10. In a multi-cylinder two-cycle internal combustion engine, the combination of a plurality of working cylinders each provided with inlet and exhaust ports arranged adjacent opposite ends thereof, a carbureter having its mixture outlet connected with the inlet port of each working cylinder, a pumping cylinder in alinement with each working cylinder, a piston in each working cylinder having an extension terminating in a head constituting a piston in the alined pumping cylinder, means for establishing communication between the several pumping cylinders and the carbureter whereby the latter is supplied with a substantially constant stream of substantially all the air so compressed in the pumping cylinders and the quantity of each charge supplied to every working cylinder exceeds that which would be obtained by the displacement of the piston therein at atmospheric pressure, and means for igniting a charge in each working cylinder.

11. In a multi-cylinder two-cycle internal combustion engine, the combination of a plurality of working cylinders each having inlet and exhaust ports adjacent opposite ends thereof, a carbureter having its mixture outlet connected with the inlet port of each working cylinder, a plurality of pumping cylinders, a piston in each pumping cylinder, an air inlet for each of the pumping cylinders, means connecting the pumping cylinders in pairs whereby the pistons therein will act as compressors throughout their entire movement, a duct connecting all of the pumping cylinders with the carbureter, whereby the latter is supplied with a substantially constant stream of substantially all the air so compressed in the pumping cylinders and the quantity of each charge supplied to every working cylinder exceeds that which would be obtained by the displacement of the piston therein at atmos-

pheric pressure, and means for igniting a charge in each working cylinder.

12. In an internal combustion engine, the combination of a casing having therein a pair of working cylinders, a pair of crank cases, a pair of pumping cylinders arranged between the working cylinders and crank cases, a piston in each working cylinder having an extension terminating in a head constituting a piston in one of the pumping cylinders, a crank shaft connected with each piston and having therein a chamber having a port constantly communicating with the adjacent pumping cylinder and a port adapted to intermittently communicate with an air inlet port in a bearing for said shaft, connections between said pumping cylinders whereby the pistons therein operate as pumping pistons throughout their entire movement, a carbureter having its mixture outlet connected with the inlet ports of both working cylinders and its air inlet connected with both pumping cylinders, and means for igniting a charge in each working cylinder.

13. In an internal combustion engine, the combination of a pair of working cylinders provided with suitable inlet and exhaust ports, means in each of said cylinders for igniting a charge, a pair of pump cylinders alined with said working cylinders and provided with air inlets, a piston in each working cylinder, a piston in each pumping cylinder connected with the piston in the working cylinder alined therewith, passageways on the exterior of said cylinders adapted to establish communication between the space on one side of a pump piston and the space on the opposite side of the other pump piston, a carbureter having its mixture outlet connected with the inlet ports of both working cylinders and having an air supply duct connected with said pump cylinders, in such a manner that all the air compressed by the pumping cylinders will be supplied to and pass through the carbureter, and means for establishing communication between said pump cylinder and said duct.

14. In an internal combustion engine, the combination of a casing having a pair of working cylinders provided with inlet and exhaust ports, means in each of said cylinders for igniting a charge, said casing also having a pair of pump cylinders alined with said working cylinders and provided with air inlets, a piston in each working cylinder, a piston in each pumping cylinder connected with a piston in a working cylinder, said casing being provided with two passageways exterior of said cylinders, each passageway being adapted to establish communication between the space on one side of one pumping piston and the space on the opposite side of the other pumping piston, a carbureter having its mixture outlet connected

with the inlet ports of both working cylinders and having an air supply duct connected with said pump cylinders and means on the piston in the working cylinder for establishing communication between said pump cylinders and said duct.

15. In an internal combustion engine, the combination of a casing having therein a pair of working cylinders having inlet and exhaust ports and a pair of pumping cylinders in alinement with the working cylinders and having air inlets, said casing having conduits for establishing communication between the pumping cylinders, a piston in each working cylinder having an extension terminating in a head constituting a piston in the alined pumping cylinder, each of said conduits establishing communication between the space on one side of a piston head in one pumping cylinder and the space on the other side of the piston head in the adjacent pumping cylinder, said casing having a common duct therein, a manifold connecting said duct with the inlet of each of said working cylinders, a carbureter inclosed in said manifold, each piston having channels adjacent the head to establish communication at intervals between the pumping cylinder and the duct, and means for igniting the charge in each cylinder.

16. In an internal combustion engine, the combination of a casing having therein a pair of working cylinders provided with suitable inlet and exhaust ports, means in each of said cylinders for igniting a charge, said casing also having a pair of pump cylinders alined with and supporting the part of the casing inclosing the working cylinders, a pair of crank cases communicating with the pump cylinders and supporting the casing comprising the pump cylinders, a piston in each working cylinder, a piston in each pump cylinder connected with a piston in the alined working cylinder, said casing being provided with two passageways exterior of said cylinders and within the casing walls, each passageway being adapted to establish communication between the space on one side of one pumping piston and the space on the opposite side of the other pumping piston, a carbureter having its mixture outlet connected with the inlet ports of both working cylinders, an air supply duct connected with said passageways and arranged to supply compressed air to said carbureter, a crank shaft connected with each piston and having therein a chamber through which air may be supplied to the interior of the crank casing, and means for establishing communication between said pump cylinders and said duct.

17. In a multi-cylinder two-cycle internal combustion engine, the combination of a plurality of working cylinders arranged in pairs and each provided with suitable inlet

and exhaust ports, pump cylinders also arranged in pairs and in alinement with the working cylinders and pistons in said pump cylinders compressing air throughout the strokes thereof, a carbureter having its mixture outlet connected with the inlet port of each working cylinder and connections including a common duct between the pairs of pumping cylinders and the inlet to the carbureter, whereby the latter is supplied with a substantially constant stream of com-

pressed air and the explosive mixture is supplied to the cylinder under pressure and in a greater quantity than could be supplied by the displacement of the working cylinder 15 only.

In testimony whereof I affix my signature in presence of two witnesses.
